(57) **CLAIM**

The ornamental design for a control pod for communications headset, as shown and described.

DESCRIPTION

FIG. 1 is a front right perspective view of the control pod for communications headset showing our new design;

FIG. 2 is a top plan view of the control pod.

FIG. 3 is a right side view of the control pod.

FIG. 4 is a left side view of the control pod.

FIG. 5 is an elevational view of the front end of the control pod.

FIG. 6 is an elevational view of the rear end of the control pod.

FIG. 7 is bottom plan view of the control pod.

FIG. 8 shows the contour of the control pod at the cross section indicated in FIG. 3; and,

FIG. 9 shows the contour of the control pod at the cross section indicated in FIG. 3.

FIG. 1 is on an enlarged scale.

The broken lines show the environment only and are not part of the claimed design.
